(57) **CLAIM**

The ornamental design for soft fishing lure with cylinder tail design, as shown and described.

DESCRIPTION

FIG. 1 is a perspective view of a soft fishing lure showing an embodiment of my new design;

FIG. 2 is a right side view of the soft fishing lure shown in FIG. 1;

FIG. 3 is a left side view of the soft fishing lure shown in FIG. 1;

FIG. 4 is a top view of the soft fishing lure shown in FIG. 1;
FIG. 5 is a bottom view of the soft fishing lure shown in FIG. 1;

FIG. 6 is back view of the soft fishing lure shown in FIG. 1;

FIG. 7 is a front view of the soft fishing lure shown in FIG. 1;
FIG. 8 is a perspective view of a soft fishing lure showing another embodiment of my new design;
FIG. 9 is a right side view of the soft fishing lure shown in FIG. 8;
FIG. 10 is a left side view of the soft fishing lure shown in FIG. 8;
FIG. 11 is a top view of the soft fishing lure shown in FIG. 8;
FIG. 12 is a bottom view of the soft fishing lure shown in FIG. 8;
FIG. 13 is back view of the soft fishing lure shown in FIG. 8;
FIG. 14 is a front view of the soft fishing lure shown in FIG. 8;
FIG. 15 is a perspective view of a soft fishing lure showing another embodiment of my new design;
FIG. 16 is a right side view of the soft fishing lure shown in FIG. 15;
FIG. 17 is a left side view of the soft fishing lure shown in FIG. 15;
FIG. 18 is a top view of the soft fishing lure shown in FIG. 15;
FIG. 19 is a bottom view of the soft fishing lure shown in FIG. 15;
FIG. 20 is back view of the soft fishing lure shown in FIG. 15;
FIG. 21 is a front view of the soft fishing lure shown in FIG. 15;
FIG. 22 is a perspective view of a soft fishing lure showing another embodiment of my new design;
FIG. 23 is a right side view of the soft fishing lure shown in FIG. 22;
FIG. 24 is a left side view of the soft fishing lure shown in FIG. 22;
FIG. 25 is a top view of the soft fishing lure shown in FIG. 22;
FIG. 26 is a bottom view of the soft fishing lure shown in FIG. 22;
FIG. 27 is back view of the soft fishing lure shown in FIG. 22;
and,
FIG. 28 is a front view of the soft fishing lure shown in FIG. 22.
The broken lines are for environmental purposes only and do not form a part of the claimed design.
